M. KIESSLING

SNAP FASTENER

Filed Feb. 15, 1923

UNITED STATES PATENT OFFICE.

MAX KIESSLING, OF WATERBURY, CONNECTICUT.

SNAP FASTENER.

Application filed February 15, 1923. Serial No. 619,162.

To all whom it may concern:

Be it known that I, MAX KIESSLING, a citizen of the United States, residing at Waterbury, in the county of New Haven, 5 State of Connecticut, have invented certain new and useful Improvements in Snap Fasteners; and I do hereby declare the following to be a full, clear, and exact description of the invention, such as will enable others 10 skilled in the art to which it appertains to make and use the same.

The present invention relates to snap fasteners such as are commonly used on garments and ordinarily sewed in place by 15 machines.

Fasteners of this type are made in two parts, each of which has a plurality of eyes through which the attaching thread passes. In the sewing operation, a machine is used 20 which has a traveling clamp, in which is to be placed a fastener part. The clamp is slotted to receive the fasteners, which are round, and this slot is formed with parallel side walls and a curved end wall so that the 25 fasteners may be securely held in position. With a fastener in place in the clamp, the sewing is carried on by passing the needle and thread through the eyes in rotation, the clamp being moved after each stitch to present the next eye to the needle. It will be 30 obvious that, with the present round fasteners, it is necessary that the fasteners be positioned in the clamp with great care, so that the eyes will be properly located in the 35 path of the needle as the clamp travels through its closed path. Round fasteners which are to be secured in place on a garment by such an automatic stitching mechanism are sometimes provided with a notch 40 formed in their peripheries and there is a small stud formed in the clamp in such position that when the stud is received in the notch the fastener is properly centered with its eyes at the points where the reciprocating 45 needle will pass through the clamp as the clamp is moved. As the fasteners are ordinarily quite small, they are difficult to handle and the centering operation consumes much time. Furthermore, if the fasteners 50 are not exactly placed, the needle will strike the body of the fastener, with the result that the needle will be broken or else the fastener damaged so that it cannot be used.

The object of the present invention is to

overcome these difficulties and to provide a fastener which may be used on the present sewing machines without alteration of the clamp or other parts. To accomplish this result I have designed a fastener of the same 60 general construction as those now used, but so shaped that, in being placed in the clamp, the fastener will automatically centre itself with the eyes in their proper positions relative to the clamp and needle. At the same 65 time the new fastener is easier to handle both before and after it is attached, while in general appearance it is closely similar to those now used.

The preferred embodiment of the invention will be more clearly understood by reference to the accompanying drawings in which Fig. 1 shows, in perspective, those parts of a standard sewing machine by 70 which the fastener is sewed in place, Fig. 2 75 is a plan view of one fastener part, Figs. 3 and 4 are sections of the two parts of a fastener, the section being on the line 3—3 of Fig. 2. Fig. 5 is a plan view of the fastener showing the attaching threads and Fig. 6 is 80 a plan view of the end of the clamp showing the slot in which the fastener is to be placed.

In the drawings the reference character 7 designates in general the sewing machine which is provided with a needle 8 mounted 85 in a reciprocating member 9 and supplied with thread 10 which passes through an eye in the end of the needle in the usual manner.

The machine is also provided with a 90 clamp member 11 which is mounted on a working part of the machine which moves the clamp member through a closed path during the operation of the machine. As shown in Fig. 6 the clamp is provided with 95 a slot 12 at its outer end and is channelled out along the edges of the slot on its upper surface so as to provide shoulders which are to support the fastener during the sewing operation. It will be noted that the 100 rear end of the slot indicated at 13 is curved and that the side walls 14 are parallel. Accordingly a round fastener may be inserted in the clamp and moved back so that its periphery will lie in contact with the curved end of the slot. The dimensions of the slot in the clamp will of course vary with the size of the fastener used and the clamp is 105 detachably mounted on the machine so that changes may be made as necessary,

As has previously been explained, when a round fastener is placed in position in this clamp it is necessary that the fastener be properly positioned in the clamp so that the 5 eyes of the fastener will be presented to the needle so that the thread may be carried therethrough. My improved fastener is illustrated in Figs. 2 to 5, inclusive, and the contour of this fastener is, in general, 10 round but it has oppositely disposed flat portions on its edges. There are illustrated four of these flattened portions on the periphery and I find that this is the most satisfactory arrangement since it gives the fastener a symmetrical appearance. Disposed 15 in definite relation to the flattened portions of the fastener are sewing eyes 15' which are so placed with reference to these portions that when the fastener is inserted in position 20 in the clamp each eye will be disposed at one of the points which are successively placed in the path of the reciprocating needle. In the present instance the fastener is shown with four flattened portions and 25 four eyes, and the clamp is given a movement step by step through a closed path. At each step in the movement a different point lying within the slot is placed under the needle, and the present fastener is so 30 formed that as it is inserted in the slot and automatically centered by the engagement of the flattened sides with the walls of the slot, the eyes are thereby automatically located at the desired points so that they may 35 be successively presented to the needle. This fastener is to be made in various sizes and for any particular size the distance between two opposite flattened portions will be 40 substantially equal to the diameter of a round fastener of a corresponding size. It is to be understood that the clamps are made in a number of standard sizes which correspond to standard size fasteners, and the new fastener which is to fit any particular 45 clamp will be of such dimensions that the distance between its opposite flattened portions is slightly less than the width of the clamp, while the radius of the curved portions separating the flattened portions will 50 be slightly greater than one half the width of the clamp.

By constructing the fastener in the form 55 illustrated it will be clear that the fastener can only be placed in the clamp with the flattened portions lying in contact with the parallel side walls, and I have placed these flattened portions, see 15, Fig. 2, at such 60 points on the periphery of the fastener that by the co-action between the sides of the slots and the flattened portions, the fastener in being inserted in the clamp will be automatically centered in relation thereto with its eyes lying at the points where the needle 65 will pass through the clamp as the clamp moves through its closed path. Thus in

using the new fastener it is not necessary that it be mounted in the clamp and then moved about on its axis until the holes are properly disposed. Nor is it necessary to insert the fastener so that any particular portion 70 has definite location relative to the clamp. When a fastener is used which has a notch designed to receive a stud formed in the clamp, then when the fastener is placed in the clamp it must be moved about 75 until the stud enters the notch, but with the new type of fastener this centering operation is altogether dispensed with. The shape of the fastener insures that the mere insertion in the clamp will put it in the 80 proper position, since it is not possible to insert it otherwise.

It has previously been explained that the distance between the opposite flattened portions of the fastener is slightly less than the distance between the side walls 14 of the slot in the clamp. The rounded portions, however, are formed with a radius which is greater than one half the distance between these side walls. The fastener, therefore, is slightly larger than a round fastener which would have the same size number, and which would be sewed to the garment by means of a clamp of the same size. Consequently since these rounded portions are formed on a slightly greater radius than one half the distance between the flattened portions, it follows that when the fastener is inserted in the clamp the center of the fastener lies slightly farther from the rear end wall 13 than would be the case with a round fastener fitting the same clamp. Therefore, when the new fastener is to be substituted for a rounded fastener it is necessary that the clamp be slightly adjusted and moved to the rear so as to place the center of the new fastener at that point where the center of the round fastener would lie. This is necessary so that the sewing holes may be properly placed with 95 regard to the needle for the distance between the sewing holes would be the same for either fastener and the path through which the clamp travels remains the same.

Furthermore, inasmuch as the fastener has a shape which includes flattened and rounded portions it will naturally be much easier to handle. Since the fastener cannot possibly be mounted in any position except one in which it is properly centered with the eyes in proper relation to the needle, there can be no damage done either to the needle or the fastener by the needle coming in contact with the main body of the metal and the flattened portions lying in contact 110 with the slot walls prevent displacement of the fastener in the clamp during the sewing operation.

While it is clear that this invention may be applied to any standard form of fastener 115

the one which I prefer is that illustrated in Figs. 3 and 4, which show cross-sections of a pair of fastener elements having interlocking parts of the usual construction. 5 However, any of the ordinary styles of fasteners may be made in the form necessary to accomplish the desired result.

When the fastener has been properly disposed in the end of the clamp and the sewing operation commenced, the clamp will be given intermittent movements by the sewing machine so as to present one hole of the fastener after another to the needle. In 10 this way the attaching threads will pass between successive holes about the periphery of the fastener and the sewing operation is carried on until the desired number of 15 threads has been introduced. The fastener, then attached to the fabric, may be readily 20 slipped from the clamp in the usual manner.

It will be clear that a fastener made as described will be much more easily handled by the operative than ordinary round fasteners and, while thus saving time and possible damage to the needle due to carelessness, 25 this new fastener may be manufactured at no additional cost. It is not necessary, furthermore, to provide any special form of 30 clamp or to alter the sewing machine in any other way, although, as has previously been explained, a slight adjustment of the 35 clamp is necessary in order that the center of the new fastener may lie at the same point which would be occupied by the center of a round fastener inserted in the clamp.

I claim:

1. A fastener adapted to be attached to an article by a sewing machine, this fastener having a continuous peripheral rim of 40 greater thickness than the main body of the fastener, a plurality of sewing eyes disposed adjacent this rim, and a plurality of centering surfaces formed in diametrical pairs in the rim in predetermined relation 45 to the sewing eyes, the radius of the portions of the rim between adjacent centering surfaces being greater than half the diametrical distance between the opposed centering surfaces. 50

2. A fastener adapted to be attached to an article by a sewing machine and consisting of a pair of cooperating members, one of which has a central socket and the other a central stud adapted to be received in said 55 socket to hold the members together, each of these members having a continuous peripheral rim of greater thickness than the main body of the fastener, a plurality of sewing eyes disposed about the central point 60 adjacent the rim, and a plurality of centering surfaces formed in diametrical pairs in the rim in predetermined relation to the sewing eyes, the radius of the portions of the rim between adjacent centering surfaces being greater than half the diametrical 65 distance between opposed centering surfaces.

In testimony whereof I affix my signature.

MAX KIESSLING.
